(57) **CLAIM**

The ornamental design for a wall mount, as shown and described.

DESCRIPTION

FIG. 1 is a top, front, right perspective view of a first embodiment of a wall mount showing the new design; FIG. 2 is bottom, front, right perspective view thereof; FIG. 3 is a right side view thereof;

FIG. 4 is a left side view thereof;

FIG. 5 is a top plan view thereof;

FIG. 6 is a bottom plan view thereof;

FIG. 7 is a front elevation view thereof;

FIG. 8 is a bottom elevation view thereof;

FIG. 9 is a right side view thereof, shown with an unclaimed camera;

FIG. 10 is a top, front, right perspective view of a wall mount, showing the new design in an alternative angled configuration;

FIG. 11 is a right side view thereof;

FIG. 12 is a top, front, right perspective view of a wall mount, showing the new design in another alternative angled configuration;

FIG. 13 is a right side view thereof;

FIG. 14 is a top, front, right perspective view of a second embodiment of a wall mount showing the new design; FIG. 15 is bottom, front, right perspective view thereof;

FIG. 16 is a right side view thereof;

FIG. 17 is a left side view thereof;

FIG. 18 is a top plan view thereof;

FIG. 19 is a bottom plan view thereof;

FIG. 20 is a front elevation view thereof;

FIG. 21 is a bottom elevation view thereof;

FIG. 22 is a right side view thereof, shown with an unclaimed camera;

FIG. 23 is a top, front, right perspective view of a wall mount, showing the new design in an alternative angled configuration;

FIG. 24 is a right side view thereof;

FIG. 25 is a top, front, right perspective view of a wall mount, showing the new design in another alternative angled configuration; and,

FIG. 26 is a right side view thereof.

(Continued)

The even-length broken lines shown in the drawings illustrate environment and form no part of the claimed design.
